HOLYOKE, MASSACHUSETTS, A CORPORATION OF MASSACHUSETTS.

PAPER-PULP-REFINING APPARATUS.

979,885.

Specification of Letters Patent. Patented Dec. 27, 1910.

Application filed March 13, 1909. Serial No. 483,174.

To all whom it may concern:

Be it known that we, JOHN L. PERKINS,
JOHN O. STANLEY, CLESSON W. PUTNAM, and
JOHN MONTGOMERY, citizens of the United
5 States of America, and residents of Holyoke,
in the county of Hampden and State of
Massachusetts, have invented certain new
and useful Improvements in Paper-Pulp-
Refining Apparatuses, of which the follow-
10 ing is a full, clear, and exact description.

This invention relates to improvements in
paper pulp refining apparatuses of a charac-
ter of which the "Jordan engine" is prob-
ably the best known and most representative
15 type. In this class of engines is comprised
a hollow body or casing, having the form of
a frustum of a cone, through which the
pulp is passed, and provided with a shaft
extending axially therethrough carrying a
20 plug or enlargement of a general conical
form, but somewhat smaller than the cham-
ber in the casing, said plug having a plu-
rality of blades or ribs which, according to
the endwise adjustment of the shaft and of
25 the plug carried thereby, have their revolu-
ble movements comparatively near to, or
somewhat widely separated from fixed blades
or ribs convergently arranged within, and
supported by the wall of, the casing. And
30 in the class of apparatus to which this in-
vention pertains, a motor, preferably an elec-
tric motor, is provided which has a constant
driving connection with the plug carrying
shaft of the refining engine, and which, when
35 the plug shaft is longitudinally moved in
either direction is concurrently bodily moved.

The particular object of this invention is
to improve the manner of mounting the
motor which drives the refining engine with
40 capability for its movements longitudinally
relatively to the length of the refining en-
gine shaft and with reference to the means
for driving the refining engine shaft from
such motor, and still further in respect of
45 capabilities for the bodily adjustment of the
motor in a direction transversely of the line
of the refining engine shaft without inter-
fering with, or being affected by, the means
for varying the position of the motor along
50 the line of the engine shaft. And the inven-
tion consists in the combination and arrange-
ment of parts and the constructions of cer-
tain of the parts all substantially as herein-
after described in conjunction with the ac-

companying drawings and set forth in the 55
claims.

In the drawings:—Figure 1 is a perspective view of the entire apparatus comprising
the Jordan engine, the motor and the means
for adjusting the motor in consonance with 60
the adjusting movements of the engine shaft.
Fig. 2 is a side elevation of the base for the
motor and the support on which the base is
adjustably movable, the same being seen as
having its disposition at right angles to the 65
length of the Jordan engine. Fig. 3 is sub-
stantially a vertical section on line 3—3, Fig.
2. Fig. 4 is a plan view of the base for the
motor and of the support on which such base
is adjustably movable. 70

Similar characters of reference indicate
corresponding parts in all of the views.

In the drawings, A represents the ap-
proximately conical body of a Jordan en-
gine or other pulp refining engine, the same 75
understood as having, as usual, a shaft B
which extends axially through the body or
casing A,—which is hollow and has a plu-
rality of longitudinally arranged and con-
vergent ribs at proper intervals around and 80
inwardly extending from its wall, while the
said shaft of the refining engine is pro-
vided with an enlargement or plug pro-
vided with outwardly extending longitudi-
nally and convergently arranged rib form- 85
ing blades or bars; and it will be sufficient
for the purposes of this description to state
that the comparatively large hand wheel C
constitutes a rotatable element, the turning
of which is effective through the usual mech- 90
anism intervening between it and the shaft
B of the pulp refining engine to move such
shaft in either direction for the adjustment
of the blade carrying plug whereby, accord-
ing to the character of work being per- 95
formed in the engine and the quality of the
result desired, the revoluble plug carried
blades may have their movements around
within the body casing with comparatively
wide separation from the fixed surrounding 100
blade in the casing or in proximate relations
to the latter.

D represents an electric motor having on
the driving shaft thereof a sprocket wheel α
opposite a sprocket wheel β on the extremity 105
of the pulp refining engine shaft B which
is extended endwise beyond the smaller end
of the hollow engine body,—said engine

shaft having suitable journal bearings d d , as shown, and the chain c driven by the motor drives the shaft B of the pulp refining engine.

- 5   E represents a base on which the motor D is mounted; and G represents a support below the motor base on which the latter is movable in a direction parallel with the length of the pulp refining engine shaft. As 70
 10   specifically shown, the motor base E is provided with depending apertured lug-like members f f , and the support G, which rests on the floor and is made in the form of a rectangular frame, comprises opposite horizontal guide bars g g parallel with the length of the engine shaft B,—the said apertured, depending members of the motor base embracing and having sliding engagements on the said parallel guide bars g .
 15   20   H represents a screw shaft which, as clearly shown in Figs. 3 and 4, is horizontally arranged and rotatably engaged with, but restrained against endwise movement relatively to, the aforementioned support G; and its screw threaded portion which extends within the openwork or frame-like support G has a screw thread engagement with a depending member or lug h formed on or affixed to the motor base E. The said screw shaft has at its outer end a sprocket wheel i .
 25   30 j , Fig. 1, represents a comparatively long shaft for which suitable bearings are provided, such shaft ranging longitudinally outside of and under the pulp refining engine body and having sprocket wheels h and m and a sprocket wheel o is provided as an appurtenance to the rotatable adjusting device for the shaft of the refining engine and 35
 35   40   which rotatable adjusting device, as before stated, comprises the large hand wheel C,—this provision being to the end that whenever the hand wheel C is turned in either direction to endwise move in either direction, the engine shaft B, the sprocket wheel O will be correspondingly rotatively moved. A sprocket chain q runs around the one end sprocket wheel of the said externally located longitudinally ranging shaft j and around 45
 50   55   the sprocket wheel o which is appurtenant to the rotatable shaft adjustment member C; and another sprocket chain t runs around the sprocket wheel m at the other end of the shaft j and also has an encircling engagement around the sprocket wheel i on the screw shaft H. Therefore, whenever the bladed plug carrying shaft B of the Jordan engine is endwise moved in either direction as required in changes in the character of the pulp being operated on or to be produced in the engine, the motor will be bodily self-adjusting, so to speak, for no thought or care is required on the part of any operator as regards the motor which in consequence 60
 65   65   of the turning of the rotatable shaft adjust-

ed element C will be moved in the line of its own shaft exactly corresponding to the movement of the pulp refining engine shaft B, so that the driving connections between the motor and the engine shaft will never be distorted, strained, cramped or in any way deranged.

In order to properly position the motor in the initial installation of the apparatus and from time to time thereafter as may be required, the motor base E is made with slots u u , the lengths of which are at right angles to the guide bars g g ; and the foot pieces of the motor are penetrated by vertical bolts v v , the screw threaded extremities of which are passed loosely through the slots u and engage with clamp plates w w under the slotted motor base. By loosening or removing the bolts v v , the motor may have a sliding movement on its base 85 and bodily toward or away from the line of the shaft B of the Jordan engine,—a capability of manifest advantage and permitting, among other considerations, the taking up of any undue slack in the sprocket 90 chain c which is driven by the motor and in turn drives the pulp refining engine shaft, the re-tightening of the bolts being, of course, attended to after the proper adjustment has been accomplished. 95

We claim:—

1. In an apparatus of the character described, the combination with the usual longitudinally adjustable plug carrying shaft of a pulp refining engine of a sprocket 100 wheel thereon, a motor having a driving shaft offset from and in a line parallel with the plug carrying shaft, provided with a sprocket wheel thereon, and a chain arranged transversely of said shaft and running around said sprocket wheels, a base on which the motor is mounted, a support having guideways on which the motor base is movable in a direction parallel with the length of the engine shaft, a screw rotatably 105 engaged with but restrained against endwise movement relatively to said support and having a screw thread engagement with said motor base, and means for operating said screw. 110

2. In an apparatus of the character described, the combination with the longitudinally adjustable plug carrying shaft of a pulp refining engine, of a motor having a chain and sprocket wheel connection with 120 said plug carrying shaft, a base on which the motor is mounted, a support having guideways on which the motor base is movable in a direction parallel of the length of the engine shaft, a screw rotatably engaged with, but restrained against endwise movement relatively to, said support and having a screw thread engagement with said motor base and provided with a sprocket wheel, a rotatable member for longitudinally adjust- 125 130

- ing the plug carrying shaft having appurtenant thereto a sprocket wheel, a shaft ranging longitudinally of the refining engine externally thereof and having sprocket 5 wheels at opposite end portions thereof, and sprocket chains running respectively around the one end sprocket wheel of said longitudinally ranging shaft and around the sprocket wheel on said rotatable plug shaft 10 adjusting member, and another chain running around the other sprocket wheel of the last named shaft and also around the

sprocket wheel on the screw shaft which engages the motor base.
